A. E. Carlsen

Attorney

UNITED STATES PATENT OFFICE.

ENEVOLD BANG, OF MINNEAPOLIS, MINNESOTA.

DOOR-CHECK.

1,373,646.

Specification of Letters Patent.

Patented Apr. 5, 1921.

Application filed January 18, 1921. Serial No. 438,245.

To all whom it may concern:

Be it known that I, ENEVOLD BANG, a subject of the King of Denmark, residing at Minneapolis, in the county of Hennepin and 5 State of Minnesota, have invented certain new and useful Improvements in Door-Checks, of which the following is a specification.

This invention relates to door checks, and 10 the object is to provide a practical and efficient device for preventing the slamming shut of doors and the resulting noise. The invention is clearly shown in the accompanying drawing, in which;

15 Figure 1 is a horizontal sectional view of a door portion and my improved door check attached thereto, or as seen on the line 1—1 in Fig. 2.

Fig. 2 is an enlarged sectional view on the 20 line 2—2 in Fig. 1.

Referring to the drawing by reference numerals, 3 designates a door, which is shown in Fig. 1 as being almost closed in its frame 4. To the door 3 is secured in 25 horizontal position a sheet metal casing 5 in the outer end of which is secured a cylinder 6 by bolts 7. One end of the casing 5 and the cylinder 6 is closed by an end piece 8, the same having a perforation 9 30 communicating with the cylinder end. A rubber plunger or piston 10 is provided in the cylinder. Said plunger is widest at its forward end and is at that end also cupped, so that only a comparatively thin edge 11 35 will contact with the interior surface of the cylinder. The rear end of the plunger 10 is secured in one end of a connecting member 12 by means of a pin 13 and two inwardly punched tongues 14. The other end of the 40 member 12 is pivotally secured at 15 to a bell crank lever 16 which is mounted on a bolt 17. To the other arm of the bell crank lever 16 is secured a roller 18 the same being adapted to coact against the frame 4.

45 It will thus be apparent that when the door 3 is quickly shut it will not slam with a loud noise. Instead, the roller 18 will cause the plunger 10 to move forward, compressing the air in the cylinder. Such air 50 will gradually escape through the vent 9 as the door closes. When the door is again opened a spring 19 is provided which will

return the plunger 10 to its rearward position, air being admitted to the cylinder through the hole 9. It may be observed air 55 may also pass around the thin edges 11 of the plunger when the latter is drawn backward.

It is understood that suitable modifications may be made in the form and structure of this invention if such modifications come within the spirit and scope of the appended claims.

Having now therefore fully shown and described my invention, what I claim to be 65 new and desire to protect by Letters Patent is:

1. A door check consisting of a cylinder adapted to be secured to a door, a plunger slidably mounted in the cylinder, a pivotally 70 mounted bell crank lever having one arm operatively connected with said plunger, and a roller mounted on the other arm of said bell crank lever, said roller being adapted to coact with the door frame. 75

2. A door check consisting of a cylinder adapted to be secured to a door, a plunger slidably mounted in the cylinder, said plunger being cupped at its forward end, a suitably mounted bell crank lever having one 80 arm operatively connected with said plunger, and a roller mounted on the other arm of said bell crank lever, said roller being adapted to coact with the door frame.

3. A door check consisting of a cylinder adapted to be secured to a door, a plunger slidably mounted in the cylinder, spring means for retaining the plunger in rearward position, a suitably mounted bell crank lever having one arm operatively connected with 90 said plunger, and a roller mounted on the other arm of said bell crank lever.

4. A door check consisting of a cylinder adapted to be secured to a door, an end wall closing the front end of said cylinder, said 95 end wall having a perforation therein, a plunger slidably mounted in the cylinder, a suitably mounted bell crank lever having one arm operatively connected with said plunger, and a roller mounted on the other 100 arm of said bell crank lever.

In testimony whereof I affix my signature.

ENEVOLD BANG.
